UNITED STATES PATENT OFFICE.

LOUIS SCHUTTE, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

STOP-CHECK VALVE.

No. 833,420.

Specification of Letters Patent.

Patented Oct. 16, 1906.

Application filed February 14, 1906. Serial No. 300,955.

To all whom it may concern:

Be it known that I, LOUIS SCHUTTE, a citizen of the United States of America, residing in the city and county of Philadelphia, in the 5 State of Pennsylvania, have invented a certain new and useful Improvement in Stop-Check Valves, of which the following is a true and exact description, reference being had to the accompanying drawings, which form a 10 part thereof.

My invention relates to valves such as are placed in steam-pipes leading from a boiler to an engine, said valves opening freely under a normal flow of steam and closing under a 15 reverse flow.

The object of my invention is to provide means for promptly and powerfully closing such valves against the boiler-pressure and also for preventing chatter and to attain 20 these results by improved and convenient mechanism and constructive details.

The nature of my improvements will be best understood as described in connection with the drawings, in which they are illustrated, and in which—

Figure 1 is a central vertical section through a valve embodying the broader features of my invention; Fig. 2, a similar section through a modified form of valve, also embodying 30 leading features of my invention; Fig. 3, a similar section through my preferred valve construction embodying all features of my invention; Fig. 4, a cross-section on the line 4 4 of Fig. 3; and Fig. 5, a similar section 35 through a portion of a valve, illustrating a practicable modification of my invention.

Referring first to the construction of Fig. 1, A is the valve-casing, having an inlet-chamber B and outlet-chamber B' and a 40 valve-seated opening B² intervening between these chambers. The upper or outlet chamber B' has an opening at its top which is closed by the head B³, an open-ended cylinder C being secured in place by this head immediately above the valve-seat. D is the valve, which is formed with an upwardly-extending stem D' and a downwardly-extending stem D², the stem D' having secured to it the piston E, working in the cylinder C, the 45 fit between the cylinder and piston being such as to permit a restricted flow of steam past the piston into the upper end of the cylinder. The downwardly-extending stem D²

has secured to it a piston F, having an effective area somewhat greater than that of the 55 valve D and working in a cylinder H, which in this construction is secured to a base I', formed in the casting I, the cylinder above communicating through a port I² with an outlet-pipe I³, normally closed by a cock, (indicated at I⁴.) A restricted passage for steam is formed in the lower part of the cylinder H. This may be either by a loose fit of the piston F in the cylinder or by a small orifice, such as O, formed in the piston. L is a valve-closing 60 stem actuated in any convenient manner from above the valve-casing and normally retracted, but capable of being forced downward, as shown in Fig. 1, to keep the valve closed, the head L' resting on the bottom of 65 the piston E or the end of the valve-stem D', as shown. In normal operation the cock I⁴ is closed and the cylinder H below the piston filled with steam at the same pressure as that in the chamber B. Under these circumstances the valve D will be opened, leaving 70 an unobstructed passage through the casing for steam from the boiler. The restricted orifice into the cylinder C permits this cylinder also to be filled with steam at the same 75 pressure as that in the chamber B'; but by opposing any rapid fluctuation in the pressure the piston E acts to prevent any chattering of the valve on its seat, and also in case of any fall in pressure in the boiler to assist 80 in the prompt seating of the valve. When it is desired to close the valve against normal boiler-pressure, it is only necessary to open the cock I⁴, permitting the steam in the cylinder H to exhaust, whereupon the pressure on 85 the top of the piston F will at once cause the valve D to seat itself, closing off further flow of steam.

In the modification shown in Fig. 2 the valve-casing, here indicated at A', is formed 95 with an inlet-chamber B⁴ and outlet-chamber B⁵, connecting through a valve-seated port, as before, the casing being formed with an opening above the valve-seat closed by a head B³, which secures in place a cylinder C, 100 as in the before-described construction. In this construction the piston E, moving in cylinder C, is connected with a valve D through an extension D³, which is virtually a continuation of the piston, leaving a similar amount of the upper face of the valve ex-

posed to pressure. The downwardly-extending valve-stem D^2 connects, as before, with a piston F , which moves in a cylinder (indicated at H') and secured in place by the removable head J , through which is formed a port J' , connecting with an outlet-pipe which is adapted to be closed by a cock, such as I^4 . The operation of this cock is practically identical with the construction shown in Fig. 1 and need not be further described.

In both modifications heretofore described it is necessary to provide means for securing the cylinders H H' in position beneath the valve, which will permit both the cylinder and the piston working in it to be inserted from below. It is obviously advantageous, however, that the whole structure should be insertible and withdrawable through the usual top opening in the casing, and this I have provided for in the construction shown in Fig. 3, in which the valve and the ports above the valve are secured in a casing (indicated at A^2) and having inlet and outlet chambers B^6 and B^7 , in the same manner as already described in the earlier modifications. The casing in the port forming the chamber B^6 is, however, formed with a cylinder-seat K of generally cylindrical form and provided, as shown, with vertical ports K' , communicating with lateral ports K^5 . The lower chamber of this casing (indicated at K^4) connects through a port K^2 and outlet-pipe K^3 , the exhaust-pipe K^3 being provided with a cock I^4 , as already described. In this cylindrical casing K is inserted a double cylinder H^2 H^3 , the two parts being separated by a partition H^4 , below which a series of ports H^5 connect the lower cylinder H^3 with the ports K' and K^5 , a series of conically-ended bolts N serving both to lock the cylinder in position and to regulate the amount of flow through the ports K' to the ports K^5 . The downwardly-extending valve-stem has secured to it a piston F' , working in the upper cylinder H^2 , and a downwardly-extending hollow portion D^4 of the piston-rod has secured to it the piston F^2 , working in the lower cylinder-chamber H^3 . The cylinder H^2 , below the valve F' , is in free communication with the chamber K^4 , forming the end of the cylinder H^3 . In this construction it will be seen that the steam in the inlet-chamber B^6 will have restricted access to the cylinder H^2 past the loose-fitting piston F' and free access from said cylinder through the hollow stem D^4 to the bottom of the cylinder H^3 , also that the lower part of the cylinder H^3 is in restricted communication with the ports K' and the chambers B^6 and K^4 . Obviously when the outlet-cock I^4 is opened the steam escapes freely from the bottom of both cylinders, and the pressure on the tops of both pistons will at once press the pistons down and carry the valve D to its seat. The advantage of this construction is that it en-

ables me to obtain an effective piston area greater than that of the valve D , while at the same time the two tandem-set pistons and the cylinder-casing in which they work can be withdrawn and inserted through the valve-port.

In the construction shown in Fig. 5 I have indicated a construction in which the cylinder C is dispensed with, a cylinder D^6 being formed in an upwardly-extending valve-stem D^5 through a packing M , at the end of which extends a plunger-like extension L^2 of the usual valve-stem used for locking the valve D closed. Obviously this construction embodies some of the merits and advantages of the cylinder C , as described in the other modifications, and I insert it in this figure of the drawings simply to indicate that I do not wish to be confined strictly to the special construction involving the use of the cylinder D and piston E .

Having now described my invention, what I claim as new, and desire to secure by Letters Patent, is—

1. A valve-casing having in combination a stop-check valve set to open in the direction of the normal flow of fluid, one or more cylinders of greater aggregate area set in the admission side of the casing, a piston attached to the valve and fitting in the cylinder, a restricted constantly-open passage whereby the fluid in the casing will gradually enter the cylinder below the piston, a port leading from the cylinder to exhaust and a valve for opening and closing said port.

2. A valve-casing having in combination a stop-check valve set to open in the direction of the normal flow of fluid, one or more cylinders of greater aggregate area set in the admission side of the casing, a piston attached to the valve and fitting in the cylinder, a restricted constantly-open passage whereby the fluid in the casing will gradually enter the cylinder below the piston, a port leading from the cylinder to exhaust, a valve for opening and closing said port, a second cylinder set in the receiving side of the casing and a second piston also attached to the valve and fitting in said cylinder, and means whereby the fluid in the casing can gradually pass to or from the cylinder above the piston.

3. A valve-casing having in combination a stop-check valve set to open in the direction of the normal flow of fluid, two cylinders, each of smaller sectional area than the valve and together of greater area arranged in tandem in the admission side of the casing the upper ends being open thereto, two tandem pistons fitting in said cylinders and both secured to the valve, means whereby a restricted flow of fluid is permitted from the casing to the under sides of the pistons, ports connecting the tandem cylinders to exhaust and a valve for opening and closing the exhaust.

4. A valve-casing having in combination a

stop-check valve set to open in the direction of the normal flow of fluid, a cylinder-casing of less external diameter than the opening in the valve-seat having formed in it two tandem cylinders, means for securing said casing in the admission side of the valve-casing, two tandem pistons fitting in said cylinders and both secured to the valve, means whereby the fluid in the valve-casing is gradually admitted to the cylinders, ports connecting the cylinders to exhaust and a valve for opening and closing the exhaust.

5 5. A valve-casing having in combination a stop-check valve set to open in the direction of the normal flow of fluid, a cylinder-casing of less external diameter than the opening in the valve-seat having formed in it two tandem cylinders, a fixed cylinder-receiving chamber

in the admission side of the casing and having a chamber K^4 , adapted to form the bottom of the lower tandem cylinder, a port leading from said chamber to exhaust, a valve for opening and closing the exhaust, a hollow piston-rod connected to the main valve working through both cylinders and 20 opening at its end into the lower cylinder and through its side into the upper cylinder, two pistons secured to said rod and working in the tandem cylinders, and means whereby the fluid in the valve-casing has gradual admission 25 to the two cylinders.
